UNITED STATES PATENT OFFICE

152,710

DESIGN FOR A PORTABLE UPRIGHT PHONOGRAPH OR THE LIKE

Stuart F. Louchheim, Beth Ayres, Pa., assignor to Amplitone, Incorporated, Philadelphia, Pa., a corporation of Pennsylvania

Application September 6, 1947, Serial No. 141,237

Term of patent 14 years

(Cl. D56—4)

To all whom it may concern:

Be it known that I, Stuart F. Louchheim, a citizen of the United States, residing at Beth Ayres, in the county of Montgomery, State of Pennsylvania, have invented a new, original, and ornamental Design for a Portable Upright Phonograph or the like, of which the following is a specification, reference being had to the accompanying drawings, forming part thereof.

Figure 1 represents a perspective view showing the front or speaker grille side of a portable upright phonograph, embodying my design.

Figure 2 represents a perspective view showing the rear of the embodiment of Figure 1, in closed position.

Figure 3 represents a perspective view, on a somewhat reduced scale, showing the rear of the embodiment of Figures 1 and 2, with the hinged turntable assembly in open, horizontal record-playing position.

I claim:

The ornamental design for a portable upright phonograph or the like, as shown.

STUART F. LOUCHHEIM.
